SWITCH MECHANISM

John C. Yingling, Dayton, Ohio

Application March 27, 1940, Serial No. 326,217

9 Claims. (Cl. 200—33)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to pressure responsive switch mechanism for automatic pressure regulators.

Although broadly applicable as a switch operating mechanism, this invention is particularly applicable to a balloonet used in connection with an observation balloon. The balloonet is a relatively small air-filled balloon adapted to be placed internally of a balloon filled with a buoyant gas, such as helium. The balloonet obviates wasting of buoyant gas by being provided with a relief valve and an air compressor to maintain the pressure in the balloonet constant within certain limits in response to expansion and contraction of the buoyant gas in the balloon. When the balloon ascends to a region of rarefied atmosphere or is subjected to a temperature increase, the buoyant gas expands, forcing air from the balloonet by way of the relief valve. Upon descent of the balloon or a decrease in temperature resulting in contraction of the buoyant gas, the compressor automatically operates to maintain the air in the balloonet within the predetermined limits.

It is an object of this invention to provide a compressor-operating switch which is sensitive to small pressure changes, which is operated by a small force and yet which is positive in action.

It is a further object of this invention to provide a sensitive switch which positively stays in either the make or break position.

It is a still further object of this invention to utilize a coil spring as a snap spring for providing relative movement between the contact elements of a switch.

Other objects of the invention will become apparent from the following description taken in connection with the accompanying drawing, in which:

Figure 1 is a sectional view through a device incorporating the invention with some of the parts shown in elevation;

Figure 2 is a view similar to Figure 1 but showing the switch in open position;

Figure 3 is a cross-sectional view taken generally along the lines 3—3 of Figure 2; and

Figure 4 is a diagrammatic arrangement of the center line of the spring in its various positions during operation of the switch in one direction, the curves being somewhat accentuated for purpose of illustration.

Referring to the drawing:

Ballonet or container 1 has suitably connected thereto a disk 2 carrying a collar 3. A gastight connection is provided between container 1 and disk 2. Flexible member 5 sealingly connects collar 3 with diaphragm member 4, mounted to move up and down in response to the differential between the upward force exerted by spring 6 and the downward force resulting from air pressure on the upper side of the diaphragm member. Movement of the diaphragm member actuates switch-operating mechanism constituting the primary feature of this invention.

The switch is composed of contact elements 25 and 26. Pin 38 serves as a stop for resilient contact element 25 which in turn is fastened to plate 17 by bracket 23 and electrically connected by conductor wire 29 to connection 34 of commercial relay switch 35. Contact element 26 is carried by member 20 pivotally mounted by means of pin 21 on panel 17 and electrically connected by conductor wire 28 to connection 33 of the relay switch. In order that conductor wire 28 will have the least possible effect on the action of spring 16, it is made of extremely flexible material and may be arranged substantially along the center line established by pivots 21 and 24. Contacts 36 and 37 of the relay switch are connected to an outside source of electrical energy and a compressor mechanism (not shown) for maintaining the balloonet or container 1 filled with air at a predetermined pressure.

Contact between elements 25 and 26 is established and broken by coil spring 16, suitably connected to contact-element-carrying member 20 by looping an end of the spring wire about the pin 21 upon which member 20 is pivotally mounted. Member 20 is provided with a projecting portion 31, receivable in the coil of spring 16 for insuring concurrent movement of that end of the coil spring and member 20 and for a further purpose to be more fully explained hereinafter. The coil spring is similarly connected at its other end to pin 24, upon which slotted lever arm 12 is pivotally mounted. Arm 12 is provided with a projecting portion 32 corresponding to the projection 31 of member 21. Guide member 27 suitably fastened to plate 17, confines the buckling movement of spring 16 to a vertical plane.

Arm 12 is slotted at 43 to receive stud pin 15, which in turn is suitably connected to cylindrical plug 11 by being screwed therewith. Tube 18 is slotted at 44 to permit relative slidable movement between pin 15 and the tube. Cylindrical plug 11 is adjustably received and held in tube 18 by

bolt 40 threaded to correspond to the internal threads of member 11.

Relative longitudinal movement between bolt 40 and tube 10 is prevented by collar 41, cylindrical member 13, and cap 14. Collar 41 is formed integral with bolt 40; member 13 is fastened to bolt 40 by cotter pin 42; and cap 14 is screw-threaded to tube 10. Bolt 40 is freely rotatably received in cap 14.

Plate 17, carrying the switch mechanism, is 10 adjustably fastened to support 19 by bolts 22 received in adjusting slots 18 and 30.

Spring 6 is adjustably operatively positioned with respect to the diaphragm 4 by collar 7, fastened to disk 2, and ring member 8 held in 15 adjusted position by lock nut 9.

The characteristics of spring 16 with respect to length, size and stiffness of wire, number of coils, etc., is such that when the spring is attached to pivots 21 and 24 in the open position of the 20 switch shown in Figure 2, it is necessary to compress it to the extent that it will assume the curved or arced position shown in Figure 2 with its center line as shown by the curve A in Figure 4. Upward movement of the diaphragm member results in progressive flexing of the spring to where its center line assumes the positions B, C and, finally, D of Figure 4. The spring may be said to bend into a sinuous form when being moved from one to the other side of dead center 25 position. By use of projections 31 and 32, a relatively "soft" or flexible spring can be used, the center of which assumes a position sufficiently far from the center line established by the pivot points 21 and 24 to maintain the spring in its extreme positions, regardless of jarring to which the device may be subjected. The pivot points 21 and 24 may be adjustably mounted and the 30 lengths of projections 31 and 32 so selected as to give the desired "throw" to spring 16 in response to the available switch operating force resulting from a pressure change in member 4. The lengths of projections 31 and 32 together with the spacing of pivots 21 and 24 govern the transmission of the switch operative force from the diaphragm member to the pivotal contact element and consequently the operative speed of the switch. By use of this arrangement, a switch 35 responsive to one-fourth inch of water pressure has been constructed.

The operation of the device is as follows: Plug 11 is suitably adjusted to position the pin 15 in the center of the upper and lower limits of travel of tubular plunger 10, the center being established by a line through the center line of pins 21 and 24. A switch-carrying plate 17 is adjusted to suit, and the spring 6 compressed a desired amount by ring 8.

With the parts as shown in Figure 1, the switch being in closed compressor-operating position, an increase in pressure causes movement of the spring from position A in Figure 4 through position B into position C, from which it snaps into switch-opening position D. A decrease in pressure in container 4 causes the spring to assume a position on the under side of the center line of pivot 21 corresponding to position B on the upper side, thence into a position corresponding to position C, and finally the spring snaps into switch-closing position A.

In the preferred embodiment of the device, a coil spring is used because of its relatively large force transmitting properties, "soft" action and controllable throw. In the broad application of 70 75

the invention, however, a flat spring may be used in lieu of the coil spring.

The above description taken in connection with the drawing is by way of example only, it being 5 intended to be limited only by the appended claims.

I claim:

1. A switch comprising a pair of contact elements, one of which is pivotally mounted, means 10 for moving said pivotally mounted contact element into and out of electrical contact with said other contact element including: an actuating means, a pivotally mounted arm operatively connected to said actuating means to be pivoted thereby, a coil spring connected at one end to said arm and at the other end to said pivotally mounted contact element, said spring being of such length and flexibility that when attached to said pivotal contact and arm, it buckles to an arced position on one side of dead center position established by the points of pivotatation of said pivotal contact and arm, and means for confining the buckling of said spring to a given plane whereby operation of said actuating means flexes said spring from switch-opening position on one side of dead center position into and through a sinuous curve to an arced switch-closing position on the other side of dead center position.

2. A device as recited in claim 1 in which said actuating means comprises reciprocal diaphragm means having a projecting pin integral therewith and in which said pivotally mounted arm is slotted to receive said pin whereby reciprocation of said diaphragm means results in pivotatation of said arm.

3. A device as recited in claim 1 in which said actuating means comprises reciprocal diaphragm means having a projecting pin integral therewith and in which said pivotally mounted arm is slotted to receive said pin, and means for adjusting the position of said pin on said actuating means to vary the responsiveness of said switch to said actuating means.

4. In an automatic pressure regulator, diaphragm means mounted to move in response to a force differential exerted thereon, a contact switch including a pair of contact elements, one of which is pivotally mounted, and means responsive to movement of said diaphragm means for moving said pivotally mounted contact element to switch-opening and closing position including: a pivotally mounted arm associated with said diaphragm means to be operated thereby, a coil spring connected at one end to said pivotally mounted arm and at the other end to said diaphragm means, said spring being initially compressed and of such a length as to assume the shape of an arc on one or the other side of dead center position, and means for preventing lateral movement of said spring whereby said spring will assume the form of a sinuous curve in a given plane during movement from one to the other side of dead center position in response to switch-opening or closing movement of said diaphragm means.

5. In an automatic pressure regulator; diaphragm means mounted to move in response to pressure variation, a switch including a pivotally mounted contact element, and means responsive to movement of said diaphragm means for operating said switch including: a pivotally mounted lever arm connected to said diaphragm means for pivotal operation thereby, a coil spring connected at one end to said arm and at the other end to

said pivotally mounted contact element, said spring being initially compressed and of such a length as to assume the shape of an arc on one or the other side of dead center position, and means for preventing lateral movement of said spring whereby said spring will assume a sinuous shape in a given plane during movement from one to the other side of dead center position.

6. A device as recited in claim 5 and further characterized by said pivotal arm and pivotal contact having projecting portions of a preselected length receivable in the ends of said coil spring.

7. A device as recited in claim 5 and further including a pin and slot connection between said diaphragm means and said lever arm.

8. A switch comprising a pair of contact elements, one of which is pivotally mounted, and means for moving said pivotally mounted contact element into and out of electrical connection with said other contact element including; a pivotally mounted arm, an initially compressed coil spring connected at one end to said pivotally mounted contact element and at the other end to said pivotally mounted arm, said spring being relatively long and of such characteristics that it will normally assume an arced position to one

5 side of dead center position, and means for preventing lateral buckling of said spring whereby pivotatation of said arm bends said spring into and through a sinuous curve in a given plane to an arced position on the other side of dead center position.

9. In an automatic pressure regulator, diaphragm means mounted to move in response to a force differential exerted thereon, a switch including a pair of contact elements, one of which is pivotally mounted to move to make and break positions, a pivotally mounted arm, an initially compressed coil spring connected at one end to said pivotally mounted contact element and at the other end to said pivotally mounted arm, said spring being of such a length as to normally lie in the shape of an arc on one or the other side of dead center position, means for preventing lateral movement of said spring, and means operatively connecting said arm to said diaphragm means including a pin carrying member integral with said diaphragm means, said arm being slotted to receive said pin, and means for adjusting said pin with respect to said member to vary the responsiveness of said switch to movement of said diaphragm means.

JOHN C. YINGLING.
